CLAW-LEVER-AND-RACK-ACTUATED PARALLEL JAW WRENCH

Filed June 25, 1947

Inventor:
Aldo Lazzarini

UNITED STATES PATENT OFFICE

2,500,461

CLAW-LEVER-AND-RACK-ACTUATED
PARALLEL JAW WRENCH

Aldo Lazzarin, Van Nuys, Calif.

Application June 25, 1947, Serial No. 756,928

3 Claims. (CL. 81—86)

1

My invention relates to improvements in wrenches of the type having the jaws always parallel to one another regardless of the aperture to which it is held.

The objects of my invention are: First—to produce a wrench which will have a very powerful grip due to its high leverage, without permanently limiting the range of displacement of the jaws to relatively small apertures; and second—to incorporate in it certain mechanical features affording utmost ease and speed in pre-adjusting its jaws to a slightly wider aperture than that required for the work at hand.

I attain these objects with a mechanical tool whose design is illustrated in the accompanying drawings and whose operation will be henceforth described:

Fig. 1 is a view of this tool as one would see by removing one side wall of that portion which constitutes the housing. In this figure the working position represented is the open one.

Fig. 2 is a similar view as the above, but showing the wrench in the closed position.

Fig. 3 is a sectional view of the upper part of the wrench, or body (for space convenience the handle portion is broken away), along line 3—3 of Fig. 2.

Similar numerals refer to the same parts as illustrated in all figures.

A main part, designated with small numeral 1, constitutes a housing enclosing the other parts of the tool's body. It is formed by two flat walls held parallel by return portions 2 and 3. A tapering elongation 4, extending downward, forms one of the pair of handles of the wrench. Also, one of the jaws, 5, is integrally a part of the same housing, straddling the two flat walls of the same at the top.

An oblong perforation in both walls of the housing is indicated by dotted line at 6. These perforations preferably follow an oblique direction for a purpose which will be later explained. They are designed to accommodate a fulcrum pin 7 and also allow the same a certain extent of shifting motion, as respectively illustrated in Fig. 1 (down) and Fig. 2 (up). Obviously the perforations of the two walls will be perfectly aligned.

A lever 8 provides the second handle of the usual pair. Its upper portion forms a head 9 upon whose summit is cut a gear sector 10. Through an appropriate perforation co-centered with the gear sector, fulcrum pin 7 is forced in, being locked therein by friction and symmetrically protruding its ends into the perforations 6 of the side walls, as shown in Fig. 3.

A toothed bar, or rack, 11, which has a section profile similar to a T turned upside-down (see Fig. 3), is slidably fitted to suitable guiding tracks

2

12, formed at the upper edge of the walls of the housing 1 and projecting inwardly.

The teeth of such rack are intermeshable with the gear sector 10.

Both the gear sector 10 and rack 11 are as broad and strong as feasible, their teeth extending in width from wall to wall of the housing.

The other jaw of the pair, 13, is an integral part of rack 11, the latter being its sliding base.

Located between the flat walls of the housing 1 is a partition 14 which will provide a small compartment for a spring-and-ball latch 15, while a small pin 16 will retain the spring of same at the bottom and provide convenient access for assembling the parts.

The ball of said latch is pressed by the spring over and in between the teeth of rack 11, causing said rack to normally stop at a varied degree of displacement along its tracks as may be induced by manipulation.

The lever head, 9, forms a curved projection, 17, in its profile, the purpose of which is to operate as a cam.

A roller, 18, held in place by pin 19, is adjacent to said cam and will operate in contact with the latter.

A lobe 20, outgrowing from lever-head 9, has a small hole within which is hooked one end of a stretching coil spring 21. The other end of said spring is anchored by pin 22 to a point in the channel formed by the housing's handle extension 4.

Said lobe 20 of the lever-head and said coil spring 21, need not be considered essential to the operation of this invention, and may be dispensed with. In such case the lever-head 9 may be caused to drop as the handle 8 is allowed to swing open by gravity or by finger manipulation.

The normal inoperative position of this wrench would be as illustrated in Fig. 1 with the two handles, 4 and 8, spread far apart, due to the pull of spring 21. However, it may be convenient for the purpose of storage, to make possible the retention of the closed position when the wrench is not in use. A slight depression of the cam profile at the point of contact with roller 18 which corresponds to the close position of the wrench will effect that. This point is indicated by a small arrow 23 in Fig. 2.

In putting this tool to use, the first step is to spread the handles apart if they don't happen already to be. This is done with a slight jerk of the small finger's knuckle, which will immediately activate spring 21 in overcoming the small depression 23 in the cam.

The action of spring 21, not only will cause the handles to spread apart, but as the cam 17 rides over roller 18, when it has reached a certain point the whole lever-handle 8, will commence to descend and may go down as far as

allowed by the play of fulcrum pin 7 within the oblong perforations 6 of the housing walls. When this has occurred, the teeth of gear sector 10 will have become disengaged from those of rack 11. In this situation, the rack 11 is readily caused to shuttle one way or the other by hand-pressing the jaws together or, reversely, by pressing the jutting end of the rack 11 into the housing. The spring-and-ball latch will momentarily hold it in the desired position. Thus an aperture is set 10 for the wrench's jaws which is most suitable for the work to be performed, that is, an aperture slightly wider than the gripping hold will attain.

By experimentation it has been found that the effective displacement needed for the jaws to 15 serve in all situations, corresponds to slightly over the spacing of one tooth of the rack.

By wide-opening the jaws and then closing them upon the object to be gripped, a very easy and speedy adjustment is accomplished.

Now, drawing the handles together, the cam 17, surmounting roller 18, will raise the gear sector 10 upwards into engagement with the teeth of rack 11. The teeth will always mesh perfectly because the spring-and-ball latch will hold the rack and its teeth in "true" position for the approach of the gear sector. Then the cam 17, riding its arched contour over the roller 18, will allow pivoting of the handle-lever at the point where fulcrum-pin 7 sits at the top of the oblong perforations of the housing. Thus the rack 11 is impelled to slide and force the jaws to close. This is the positive gripping action. As it involves a small displacement of the jaws, and as the ratio of leverage (lever-handle length: gear sector radius), is high, its gripping power is correspondingly great.

While tension is applied upon the handles, during the gripping action, the thrust of the gear sector 10, upon the resisting rack 11, would tend to cause the meshed teeth to slide off engagement. To prevent that, the counter-thrust developed by fulcrum-pin 7, which is in the opposite direction, is taken advantage of.

The wall perforations 6, as shown in the drawings, are cut in an oblique direction. They could be vertical without prejudice to the functioning of the instrument. However, the oblique cut is preferred in order to cause a slanted rising motion of the gear sector which will obviate any displacement of the toothed rack 11 before the teeth are completely intermeshed.

To release the holding grip, it will only be necessary to ease the hand pressure from the handles. The spring 21 being under tension will pull on lobe 20 and cause all moving parts to return to the open position.

Having thus described my invention, I claim:

1. A parallel wrench composed of a housing body having two main walls, a forwardly projecting stationary jaw adjacent one edge and a fixed handle extending rearwardly at the opposite edge, a movable jaw opposing said stationary jaw and having a toothed rack slidable transversely within the housing body, a stationary roller, a composite element forming a lever and a head with a gear sector at one end and opposing the teeth of the rack, said head also having a cam profile, the latter being operable upon the roller, said roller being positioned within the housing between the fixed handle and the cam profile of the head, a fulcrum pin transversing said head coaxially with the gear sector and projecting with both ends into a pair of co-aligned oblong perforations of the two main walls of the housing body, said perforations allowing sufficient play of the fulcrum pin to permit the engaging and disengaging of the gear sector and the toothed rack; and a spring normally acting to cause the composite element to swing in the open position.

said head coaxially with the gear sector and projecting with both ends into a pair of co-aligned oblong perforations of the two main walls of the housing body, said perforations allowing sufficient play of the fulcrum pin to permit the engaging and disengaging of the gear sector and the toothed rack; and a spring normally acting to cause the composite element to swing in the open position.

2. A parallel wrench composed of a housing body having two main walls, a forwardly projecting stationary jaw adjacent one edge and a fixed handle extending rearwardly at the opposite edge, a movable jaw opposing said stationary jaw and having a toothed rack slidable transversely within the housing body, resilient stop means for restraining the sliding motion of said toothed rack, a stationary roller, a composite element forming a lever and a head within a gear sector at one end and opposing the teeth on the rack, said head also having a cam profile, the latter being operable upon the roller, said roller being positioned within the housing between the fixed handle and the cam profile of the head, a fulcrum pin transversing said head coaxially with the gear sector and projecting with both ends into a pair of co-aligned oblong perforations of the two main walls of the housing body, said perforations allowing sufficient play of the fulcrum pin to permit the engaging and disengaging of the gear sector and the toothed rack; and a spring normally acting to cause the composite element to swing in the open position.

3. A parallel wrench composed of a housing body having two main walls, a forwardly projecting stationary jaw adjacent one edge and a fixed handle extending rearwardly at the opposite edge, a movable jaw opposing said stationary jaw and having a toothed rack slidable transversely within the housing body, resilient stop means for restraining the sliding motion of said toothed rack, a stationary roller, a composite element forming a lever and a head with a gear sector at one end and opposing the teeth on the rack, said head also having a cam profile, the latter being operable upon the roller, said roller being positioned within the housing between the fixed handle and the cam profile of the head, a fulcrum pin transversing said head coaxially with the gear sector and projecting with both ends into a pair of co-aligned oblong perforations of the two main walls of the housing body, said perforations allowing sufficient play of the fulcrum pin to permit the engaging and disengaging of the gear sector and the toothed rack; and a spring normally acting to cause the composite element to swing in the open position.

45. A parallel wrench composed of a housing body having two main walls, a forwardly projecting stationary jaw adjacent one edge and a fixed handle extending rearwardly at the opposite edge, a movable jaw opposing said stationary jaw and having a toothed rack slidable transversely within the housing body, resilient stop means for restraining the sliding motion of said toothed rack, a stationary roller, a composite element forming a lever and a head with a gear sector at one end and opposing the teeth on the rack, said head also having a cam profile, the latter being operable upon the roller, said roller being positioned within the housing between the fixed handle and the cam profile of the head, a fulcrum pin transversing said head coaxially with the gear sector and projecting with both ends into a pair of co-aligned oblong perforations of the two main walls of the housing body, said perforations allowing sufficient play of the fulcrum pin to permit the engaging and disengaging of the gear sector and the toothed rack; and a spring normally acting to cause the composite element to swing in the open position.

40. A parallel wrench composed of a housing body having two main walls, a forwardly projecting stationary jaw adjacent one edge and a fixed handle extending rearwardly at the opposite edge, a movable jaw opposing said stationary jaw and having a toothed rack slidable transversely within the housing body, resilient stop means for restraining the sliding motion of said toothed rack, a stationary roller, a composite element forming a lever and a head with a gear sector at one end and opposing the teeth on the rack, said head also having a cam profile, the latter being operable upon the roller, said roller being positioned within the housing between the fixed handle and the cam profile of the head, a fulcrum pin transversing said head coaxially with the gear sector and projecting with both ends into a pair of co-aligned oblong perforations of the two main walls of the housing body, said perforations allowing sufficient play of the fulcrum pin to permit the engaging and disengaging of the gear sector and the toothed rack; and a spring normally acting to cause the composite element to swing in the open position.

45. A parallel wrench composed of a housing body having two main walls, a forwardly projecting stationary jaw adjacent one edge and a fixed handle extending rearwardly at the opposite edge, a movable jaw opposing said stationary jaw and having a toothed rack slidable transversely within the housing body, resilient stop means for restraining the sliding motion of said toothed rack, a stationary roller, a composite element forming a lever and a head with a gear sector at one end and opposing the teeth on the rack, said head also having a cam profile, the latter being operable upon the roller, said roller being positioned within the housing between the fixed handle and the cam profile of the head, a fulcrum pin transversing said head coaxially with the gear sector and projecting with both ends into a pair of co-aligned oblong perforations of the two main walls of the housing body, said perforations allowing sufficient play of the fulcrum pin to permit the engaging and disengaging of the gear sector and the toothed rack; and a spring normally acting to cause the composite element to swing in the open position.
